Application September 23, 1948, Serial No. 50,737

4 Claims. (Cl. 175—320)

1

This invention relates to a detection device for use in the detection of the displacement of a magnetizable body in a particular predetermined direction.

An object of the invention is the improvement of detection devices employed in detecting the displacement of magnetizable bodies.

More particularly the invention is an improved displacement detection device comprising a detection coil and an improved relay device responsive to the potential waves generated in the coil. The coil is wound on a magnetic core, and is so disposed in relation to the line of motion of a displaceable magnetizable body as to generate a potential wave in response to the displacement of the body. The potential wave is impressed on the improved relay device of the present invention and in response thereto the improved relay provides a signal if the movement is in a particular predetermined direction. Such a device may be used to advantage, for instance, in controls for vehicular traffic where directional discrimination is essential.

There are presently known in the art, particularly in the vehicular traffic control art, a number of devices which perform the same fundamental function as does the relay of the present invention. However, so far as is known, there is no relay which is operated in response to displacement of a vehicle and which affords directional discrimination in a vehicular traffic control which is not subject to failure under one or another operating condition. In certain of these devices, for instance, the directional discrimination afforded by the device depends on the traverse of two magnetic detecting coils which are so spaced in the roadway that they are activated in sequence by a moving vehicle. Directional discrimination is afforded by the activation of the detecting devices in sequence in a particular order. For instance, for one direction of travel detecting device 1 is first activated followed by the activation of detection device 2. The relay may be arranged to provide a positive indication for this particular mode of operation whereas traverse in the opposite direction resulting in the actuation first of detector 2 followed by the actuation of detector 1 would provide no indication. In certain of the devices designed for operation on this principle a chain of operation is initiated say by the activation first of detector 1. In order to complete the conditions under which the relay provides a positive indication, it is necessary that detector 2 be activated within a particular interval after

2

detector 1 operates. The rate of traverse of vehicles varies widely from say a fraction of a mile per hour for a heavily loaded truck to speeds which may in some cases exceed seventy or eighty or more miles an hour. The requirements imposed on the presently known relays for such conditions are very severe, more severe than can be met. Relays operating in conjunction with sequentially traversed detectors are set so as to be operative over a certain average range of speeds and are therefore limited in their application to service where such operation will suffice.

Each other known form of magnetic vehicular control which is operative in response to movement of a vehicle and which affords directional discrimination is subject to some limitation in its operation which can be revealed by study of the proposed device and for this reason they have not been widely applied for this purpose although magnetic detectors are widely used in applications where directional discrimination is not required.

The present relay does not depend upon the sequential traverse of a number of detecting devices. A single detecting device, which may for instance be a single coil wound on a magnetizable core, disposed in such manner that the flux traversing the core due to the earth's magnetic field is changed so that a voltage wave is generated in response to the displacement of the magnetizable body, such as the movement of a motor vehicle in the vicinity of the detecting device, is all that is necessary to control the present relay.

It is well known that the pattern of the generated voltage waves in a detecting coil is different for opposite directions of displacement of the magnetizable body. In particular it has been found that if, for instance, the displacement of the body in a first direction generates a voltage wave, the first pulse of which is positive, displacement in the opposite direction will generate a voltage wave the first portion of which is negative. The patterns of the generated voltage waves vary depending upon the shape and mass of the displaced magnetizable body, the direction and intensity of the earth's magnetic field at the particular point, the characteristics of the detecting coil and the disposition of the detecting coil with respect to the direction of displacement. Since, however, for all conditions the first pulse of the generated voltage wave is positive for one direction of displacement and negative for the opposite direction, advantage may be taken of this characteristic to afford discrimination if

the cooperating relay is made responsive to the first pulse of a wave which is, for instance, positive and non-responsive to a first pulse which is negative and if it can be arranged so that it is unaffected by subsequent pulses in the wave. This can be performed for instance by means of an electron device which discriminates between the positive and negative first pulses. However, the pattern of the voltage wave which is produced under certain circumstances may be quite protracted and contain as many as four or five or more positive and negative peaks for a single traverse or displacement in one direction. There is not presently available in the art an electronic relay which will respond to a first pulse of a particular polarity and remain unaffected by the subsequent variations in an inordinately irregular wave of the longest required duration. The relay of the present invention meets this requirement.

The invention may be understood from the following description when read with reference to the associated drawing which discloses a preferred embodiment in which the invention may be incorporated. It is to be understood, however, that the invention is not limited to the particular embodiment described herein but may be incorporated in other embodiments which will readily suggest themselves to those skilled in the art.

In the drawings,

Fig. 1 shows the relay of the present invention; and

Figs. 2 and 3 show graphs of voltage waves impressed on the relay.

Refer now to Fig. 2 which shows two voltage waves A and B which are generated by the displacement of a magnetizable body with reference to a detecting device consisting of a current conducting coil wound on a magnetic core, which device is located in close proximity to a displaceable magnetic body. The body, which may for instance be a bar of iron passing over the detecting device, generates a train of three pulses as shown in Fig. 2 for each traverse. The train for one direction of traverse is different from the train for the opposite direction of traverse. For one direction, as shown by the curve designated A, in Fig. 2, the train consists of a large positive pulse separating two small negative pulses. For the opposite direction, as shown by the curve designated B in Fig. 2, the train is the same but the pulses are reversed in polarity with respect to the pulses of curve A.

Attention is particularly directed to the fact that the first portion of pulse A is negative whereas the first portion of pulse B is positive. This opposite polarity of the first portion of a voltage wave is characteristic of all voltage waves generated in detection coils in response to opposite directions of displacement of magnetic material with respect to the coil.

Fig. 3 shows two voltage waves A and B generated in a detection coil due to the traverse of the coil by a moving motor vehicle. Curve A is for traverse in one direction. Curve B for traverse in the opposite direction. The waves are irregular and one is only approximately the inverse of the other, but the first pulse of A is positive while the first pulse of B is negative. It has been found that for a particular location of the coil and for all vehicles moving in a particular direction the polarity of the first pulse is always uniform and it is always uniform and opposite for the opposite direction of travel.

Attention is particularly called to the irregu-

larity of the wave pattern of voltage wave A and of voltage wave B in Fig. 3. Each of these waves has several positive and negative peaks. If a relay is to be designed to respond to the first portion of a wave, which portion is of a particular polarity, in order to be effective it must be arranged so that it is unaffected by the succeeding pulses of the wave. The relay of the present invention is so arranged. The manner in which this is achieved will now be described.

Refer now to Fig. 1. Fig. 1 may be considered to be divided into four portions, namely a detecting coil, shown at the upper left in Fig. 1, in which the voltage wave patterns such as those shown in Figs. 2 and 3 are generated, an amplifier shown in the middle of Fig. 1, a pulse discriminating relay arrangement shown at the upper right, and a power supply shown at the lower right. Terminals 1 and 2 are the input terminals to the amplifier. Terminals 3 and 4 are the output terminals of the relay arrangement and terminals 5 and 6 are the alternating current supply terminals. An alternating potential is supplied from terminals 5, 6 to the primary of transformer TR2. The plate voltage for the amplifier is supplied through rectifier VT4 and the voltage for the relay from rectifier VT7. The cathode heater supply is furnished from the bottom right-hand secondary coil to all tubes.

The detecting coil is preferably disposed in such manner that the moving magnetizable body, such as a moving vehicle, traverses the coil and the differences between the distinguishable first portions of the voltage waves are most pronounced. The terminals of the coil are connected to the input terminals 1, 2 of an amplifier, which may, for instance, be a three-stage amplifier. The amplifier may comprise, for instance, three indirectly heated duo triode vacuum tubes, VT1, VT2 and VT3, one in each stage and having their respective half sections VT1, 1 and VT1, 2, VT2, 1 and VT2, 2, VT3, 1 and VT3, 2 arranged in push-pull relation. The stages may have resistance capacitance coupling. Although a three-stage push-pull resistance capacitance coupled amplifier is illustrated, the invention may be practiced with amplifiers of other types so long as the output of the amplifier, in response to the voltage wave generated in the coil 1, is adequate to control the pulse discriminating relay arrangement of the present invention connected to the amplifier output through the double pole double throw switch and the transformer TR1. The double pole double throw switch is arranged to control the direction of the amplifier output pulses applied to transformer TR1 so that the polarity of the pulse applied to the pulse discriminating relay arrangement will operate it for any chosen direction of traverse and will not operate it for the opposite direction of traverse.

The pulse discriminating device in a preferred embodiment comprises essentially the duo diode shown in Fig. 1 as VT5, 1 and VT5, 2, the duo triode VT6, and two magnetic relays RL1 and RL2 together with a time control circuit for each section of duo-triode VT6, which controls the operation of relays RL1 and RL2, comprising capacitance C15 and resistance R21 for relay RL1, and capacitance C16 and resistance R23 for relay RL2.

Normally when no voltage wave is being generated in the detecting coil and no pulses are impressed therefore through transformer TR1, both sections VT5, 1 and VT5, 2 of the duo diode are inactivated. For this condition the right-hand

section of duo-triode VT₆ is activated. The left-hand section of duo-triode VT₆, due to the connection of cathode resistor R₂₂, is inactivated. Relay RL₂ in the plate circuit of the right-hand section of VT₆ is therefore operated. The relay RL₁ in the plate circuit of the left-hand section of VT₆ is normally released and its two pairs of contacts 7 and 8, 9 and 10, respectively, are normally open. When relay RL₂ is operated both armatures 11 and 14 are raised, armature 11 disengages from contact 12 and armature 14 engages with contact 13 so that contacts 11 and 12 are open and contacts 13 and 14 are closed. For this condition the circuit to the indicator terminals 3, 4, which includes contacts 9 and 10, 13 and 14, is open since contacts 9 and 10 are open.

It will be assumed that the first pulse as it appears on the secondary of transformer TR₁ is negative. In response to this, section VT₅, 2 will conduct, whereas section VT₆, 1 will not conduct.

When duo diode section VT₅, 2 conducts, the potential of the right-hand grid of duo triode VT₆ is made more negative with respect to its cathode. This inactivates the right-hand section of VT₆, in turn releasing relay RL₂, thereby closing contacts 11 and 12, and opening contacts 13 and 14. The open condition of the indicator circuit through terminals 3 and 4 will be insured for this condition as contacts 13 and 14 will be open in addition to contacts 9 and 10, which of course remain open.

The closing of contacts 11 and 12 when relay RL₂ releases short circuits the left-hand grid cathode circuit of duo triode VT₆ to prevent the activation of the left-hand section of VT₆ in response to subsequent positive pulses in the voltage wave. This circuit remains short circuited as long as relay RL₂ remains released. The time constant of the bias circuit comprising capacitance C₁₆ and resistance R₂₃ is such that the right-hand section of duo-triode VT₆ remains non-conducting for an interval longer than the duration of the incoming train of pulses. It is for this reason that subsequent positive pulses cannot operate relay RL₁ since the grid cathode circuit of the left-hand section of duo diode VT₆ remains short-circuited throughout this interval. Further negative pulses will simply insure that relay RL₂ remains released. At the end of the measured interval the negative bias will be removed from the grid of the right-hand section of duo triode VT₆. Relay RL₂ will reoperate closing contacts 13 and 14, opening contacts 11 and 12 and removing the short circuit from the grid cathode circuit of the left-hand section of VT₆.

It will now be assumed that the first pulse is positive. In response to this, section VT₅, 1 will conduct. Section VT₅, 2 will not conduct. When section VT₅, 1 conducts the left-hand grid of duo triode VT₆ will be made more positive with respect to its cathode, activating the left-hand section and operating relay RL₁ which closes both of its pairs of contacts 7 and 8, 9 and 10. The closing of contacts 7 and 8 short-circuits the grid cathode circuit of the right-hand section of duo triode VT₆ so that it will remain unaffected by subsequent negative pulses in the voltage wave presently being received. The closing of contacts 9 and 10 closes the circuit to the indicator terminals since now both pairs of contacts 9 and 10, 13 and 14 are closed simultaneously. The closing of the circuit through the indicator terminals 3, 4 will control the indicator, not shown, so as to indicate the condition.

In a preferred embodiment of the invention, the

magnitudes of the resistances, capacitances and volume control and the codes of tubes corresponding to the designations shown in Fig. 1, which afford satisfactory operation, are as follows:

	Resistors	Ohms
5	R ₁	5,000
10	R ₂	200,000
	R ₃	5,000,000
	R ₄	400,000
	R ₅	1,200
	R ₆	400,000
	R ₇	10,000,000
	R ₈	5,000,000
	R ₉	1,200
	R ₁₀	5,000,000
	R ₁₁	200,000
	R ₁₂	200,000
	R ₁₃	200,000
20	R ₁₄	6,000,000
	R ₁₅	5,000,000
	R ₁₆	5,000,000
	R ₁₇	15,000
25	R ₁₈	400
	R ₁₉	15,000
	R ₂₀	10,000
	R ₂₁	1,000,000
	R ₂₂	1,500
	R ₂₃	(critical)
	R ₂₄	1,000,000

	VT ₆	6SN7
65	VT ₇	5Y3

What is claimed is:

1. A traffic indicator control for regulating vehicular motor traffic, said control comprising a detecting coil, and an amplifier, said coil connected through said amplifier to a first and a second unidirectional conducting element, said elements oppositely poled, said elements connected in parallel across the output circuit of said amplifier, said coil and amplifier responsive to the passage of a magnetizable material past said coil

in a first direction and in a second direction, opposite from said first direction, to make said first and said second element selectively conducting at a first and a second time, respectively, a first and a second space discharge device each having an input circuit and an output circuit, a first and a second parallel connected resistance and condenser timing circuit connected individually in series with said first and said second unidirectional conducting elements respectively, said input circuits of said first and said second space discharge device being connected individually across said first and said second timing circuit respectively, a first and a second magnetic relay, an individual winding on each of said relays connected in said output circuit of said first and said second space discharge device respectively, a first control circuit, for said second space discharge device, responsive to said first relay, connected to said input circuit of said second space discharge device, a second control circuit, for said first space discharge device, responsive to said second relay connected to said input circuit of said first space discharge device, said control circuits for preventing pulses of a signal train following the first pulse from affecting its connected space discharge, and a circuit path cooperably controlled by said first and second relays.

2. A traffic indicator control in accordance with

claim 1 having a switch connected between said coil and said unidirectional conducting elements to reverse the polarity of pulses applied to said elements.

- 5 3. A traffic indicator control in accordance with claim 1 including means for making said first space discharge device normally conducting and means for making said second space discharge device normally non-conducting.
- 10 4. A traffic indicator control in accordance with claim 1 including a resistor connected directly in series with a cathode in said second space discharge device.

GEORGE GLINSKI.
